BEDSPRING LIFTING DEVICE

Louis Herzog, Brooklyn, N. Y., assignor of one-half to Joseph Miller, Brooklyn, N. Y.

Application March 23, 1939, Serial No. 263,666

4 Claims. (Cl. 5—323)

My present invention relates to bed spring lifting devices and more particularly to the type whereby the bed spring is adapted to be swung upwardly and so maintained that access is had to the underside of the spring and to the floor space normally "under the bed" to facilitate cleaning.

The principal object of this invention is to provide a device of the character mentioned of novel and improved construction, which is adapted to be detachably mounted onto any bed structure having an unattached spring.

Another object is to provide a novel and improved bed spring lifter of the type described which requires a minimum of skill to install, a minimum of parts to be attached, and a minimum of effort to operate.

A further object is to provide a novel and improved device of the character set forth, whereby there is an absence of tendency to jump up or fall down when let go after the spring is shifted from horizontal rest position.

Another object of this invention is to provide a bed spring lifter of novel and improved construction, whereby after the spring has been swung to an upward tilted position, it automatically is shifted into a stable upheld position.

Another object hereof is to provide a device of the character described, the construction of which is extremely compact and is adaptable for use for all types of beds.

A further object is to provide a novel and improved bed lifting device which is simple in construction, reasonably cheap to manufacture, easy to use, and efficient in carrying out the purposes for which it is designed.

Other objects will become manifest as the following disclosure proceeds.

In the drawings forming part of this application, similar characters of reference indicate corresponding parts in all the views.

Fig. 1 is a perspective view, partly fragmentary, illustrating one form of bed equipped with an embodiment of the present invention; the spring being shown in raised position.

Fig. 2 is a fragmentary perspective view showing a bed equipped with a modified form of a bed lifting device following the teachings of this invention; the spring being shown in raised position.

Fig. 3 is a partly fragmentary section taken at line 4—4 in Fig. 1 showing the spring in normal position.

Fig. 4 is a partly fragmentary section taken

at line 4—4 in Fig. 1 showing the spring in ultimate raised rest position.

Fig. 5 is a slightly enlarged fragmentary section taken at line 5—5 in Fig. 1.

Fig. 6 is a diagrammatic slightly reduced end view showing a clamping device included when the bed lifter is used with a spring known as the "box" type.

Fig. 7 is a fragmentary sectional, slightly reduced end view of a further modified form of spring lifting structure in accordance with this invention, adaptable for use with all types of springs and especially for "box" springs.

In the drawings, the numeral 15 indicates generally a foldable brace comprising a pair of preferably flat bars linked at a point 16 which is near the respective ends of each to form an X-shaped structure. The other end of one of said bars which is numbered 17, is pivotally secured in any suitable manner at one side of the bed 18, as at point 19, while the other end of the second bar which is designated by the numeral 20, is pivotally secured in any suitable manner at one side of the bed spring 21, as at point 22.

Any desirable permanently or detachably secured means may be mounted along the side of the bed and along the line of the spring to provide such pivot points 19 and 22, as for instance, the clamping means indicated generally by the numerals 23 and 24. For a balanced construction, a pair of such braces 15 are used, either near one another and centrally positioned with respect to the bed 18 as in Fig. 1, or else, one such brace 15 at each end of the bed as partially shown in Figs. 2 and 7 of the drawings.

Intermediate the pivot points 16 and 19, and at the remote free end of the bar 17, are lugs 25 and 26, which extend respectively towards the other side of the bed 18. A coil spring 27 is secured at one end to the extreme free end of the lug 25 at point 28, and the other end of said spring is secured to the remote free end of the bar 20 at point 29. Another coil spring 30 is secured at one of its ends to the extreme free end of the lug 26 at point 31, while the other end of said second spring is secured to point 32 on bar 20, which latter point is intermediate the pivot points 16 and 22.

It is to be noted that with the bars 17 and 20 collinear when the brace 15 is unfolded, the spring 30 is untensed, while spring 27 is in tensed condition and out of line of said bars. These bars are urged by the momentum imparted to them, to a relatively crossed position as shown in Fig. 2, but the extent of such motion and

their ultimate position is determined by the stop bar which may include point 31 and said stop member may be designated by the numeral 33. The set up is now in stable condition, considering that the bed spring 21 is pivotally mounted along its other edge about an axis 34.

This axis 34 may be provided at the top end of the upwardly extending members 35, mounted one onto each of the cross slats 36, which span the bed frame at its head end and front end respectively. Pivotally secured at 34, is the upper end of the normally upright arm 37 of an angle member 38, one of the latter at each arm 35, so that the bed spring 21 may rest on the normally horizontal arms 39 of said angle members.

Or else, as in Fig. 7 such axis, now designated by the numeral 34' may be provided on a bracket 40—one such bracket for each brace 15,—straddling as at 41, or otherwise suitably mounted or secured at such side of the bed 18. In this construction the normally horizontal arms 39' of the angle members 38', extend substantially across the entire width of the bed spring 21 to support the latter, which just lies thereon, a preferable condition for all types of bed springs and especially for the box type 21'. A mattress support arm 42 is pivotally secured at one end at 43 or 43', one onto each of the arms 31 or 37' as the case may be, so that said support arms 42 can be swung to downward position as in Fig. 3, or in mattress-supporting upward position in Figs. 2 and 4. In the embodiment of this invention as shown in end view of Fig. 7, it is evident that the members 35 and 38 may be omitted on the slats 36 in such set-up, and if the braces 15 are far enough apart to lend proper support to the bed spring 21, then even the slats 36 may be dispensed with.

Bar 20 is made in two parts so that its length may be adjustable by means of bolts through registerable holes 44, or by means of channel and slide construction shown at 55 adapted to be fixed by bolt 56. Slat 36 to be adjustable for beds of various widths, is provided with a channel member 45 slidable thereon at its end and adapted to be secured in necessary position by means of bolt and nut 46. An arm indicated by the numeral 47 extends slightly spaced below the side rail 48 of the bed 18 in order to prevent the slat 36 from shifting upward at any time.

When the bed spring is of the link type, attachment may be onto the pipe frame members 49 thereof, as for instance, by hook and nut 50 and a suitable clamp construction as illustrated by the numeral 24 generally. Of course, pivot point 22 may be provided by any member, as for instance, 51 directly secured to the side of the bed spring. However, in order to avoid marring by screw holes, any suitable clamp as 52 for example, may embrace the spring 21 which is a provision desirable with the box spring type. Any suitable means as the screw means 53 may be used to loosen or tighten the clamp 52 onto the bed spring 21.

It is evident that a pair of units each comprised of a brace 15 in pivotal association at 54 with slat 36 and the member 35 with all it carries mounted on said slat as aforescribed, as illustrated in Fig. 2, may be adapted for any style bed. The slat 36 may rest across strips 55 in wooden bed structures illustrated in the drawings, or otherwise suitably placed or mounted to bridge the bed frame of other bed constructions, or such units may either lie on the floor

in spaced relation connected by a detachably mounted cross bar 56 as the stop means heretofore described, namely, analogous to the stop bar 33. It is preferred that the tension spring 27

5 shall be of stronger construction than the tension spring 30 so that the work of opening the brace 15 shall fall primarily upon spring 27, while spring 30 for the most part, shall act as an auxiliary and primarily for the purpose of 10 shifting the brace bars 17 and 20 out of colinear position to stable position as illustrated in Fig. 1 with the bed spring 21 in raised position.

The downward action of the weight of the bed spring 21 and the mattress 51 it carries shall 15 slightly exceed or at least act to counterbalance the action of the tension springs 27 and 30 to raise said bed spring and mattress.

In operation, to lower the bed spring 21, rod 33 is gotten hold of and constantly pushed forward by the person handling same, so that the brace components 17 and 20 become colinear and then assume an intersecting relation. This rod 33 is then let go, and the bed spring 21 pushed downward thus stressing the coil springs 30 and 25 27 for readiness for the lifting operation, which is obvious.

This invention is capable of numerous forms and various applications without departing from the essential features herein disclosed. It is 30 therefore intended and desired that the specific embodiments shown and described herein be deemed illustrative and not restrictive and that the patent shall cover whatever features of patentable novelty exist herein; reference being had to the following claims rather than to the specific description herein to indicate the scope of the invention.

I claim:

1. In a device for tilting a bed spring on the 40 frame of a bed, the combination of means for pivotally connecting the bed spring at a point fixed with respect to one side of the bed frame, a foldable brace adapted to lie under the bed spring comprising a pair of bars, one of which is of the extensible type, pivotally secured to each other intermediate their lengths; an end of one of said bars being pivotally mounted on the underside of the bed spring at a point spaced from the first mentioned pivotal connection and an 50 end of the other of said bars being pivotally mounted at a point fixed with respect to the bed frame and spaced from said first mentioned pivotal connection, a lug extending from one of the bars, a stop means on one of said bars, a coil spring secured at its ends to the lug and the other bar respectively whereby when the bars are extending colinearly said coil spring is in tilted relation with said bars; said coil spring being adapted then to automatically shift said bars into intersecting relation past dead center until said stop means limits such shifting of the bars, and another coil spring secured at one of its ends to one of said bars and at the other of its ends to the second bar adapted, when the bed spring 55 is in normal horizontal position, to urge the bars towards the aforesaid dead center position.

2. In a device for tilting a bed spring on the frame of a bed, the combination of means for pivotally connecting the bed spring at a point fixed with respect to one side of the bed frame, a foldable brace adapted to lie under the bed spring comprising a pair of bars, one of which is of the extensible type, pivotally secured to each other intermediate their lengths; an end of one of said bars being pivotally mounted on the un-

derside of the bed spring at a point spaced from the first mentioned pivotal connection and an end of the other of said bars being pivotally mounted adjacent the other side of the bed, a lug extending from one of the bars, a stop means of one of said bars, a coil spring secured at its ends to the lug and the other bar respectively whereby when the bars are extending colinearly said coil spring is in tilted relation with said bars; said coil spring being adapted then to automatically shift said bars into intersecting relation past dead center until said stop means limits such shifting of the bars, and another coil spring secured at one of its ends to one of said bars and at the other of its ends to the second bar, adapted when the bed spring is in normal horizontal position, to urge the bars towards the aforesaid dead center position.

3. In a device for tilting a bed spring on the frame of a bed, the combination of a slat adapted to lie under the bed spring and transverse the bed frame, means for pivotally connecting the bed spring at one end of the slat, a foldable brace comprising a pair of bars, one of which is of the extensible type, pivotally secured to each other intermediate their lengths, an end of one of said bars being pivotally mounted at a point spaced from the aforesaid pivotal connection to the underside of the bed spring and an end of the other of said bars being pivotally mounted on the slat at a point spaced from the first mentioned pivotal connection, a lug extending from one of the bars, a stop means on one of said bars, a coil spring secured at its ends to the lug and the other bar respectively whereby when the bars are extending colinearly said coil spring is in tilted relation with said bars; said coil spring being adapted then to automatically shift said bars into intersecting relation past dead center

5 until said stop means limits such shifting of the bars, and another coil spring secured at one of its ends to one of said bars and at the other of its ends to the second bar, adapted when the bed spring is in normal horizontal position, to urge the bars towards the aforesaid dead center position.

10 4. In a device for tilting a bed spring on the frame of a bed the combination of a slat adapted to lie under the bed spring and transverse the bed frame, an elongated member lying under the bed spring substantially parallel with said slat, adapted to support said bed spring; the slat and said member being pivotally connected at one of their respective ends, a foldable brace comprising a pair of bars, one of which is of the extensible type, pivotally secured to each other intermediate their lengths; an end of one of said bars being pivotally secured to said member at a point spaced from the first mentioned pivotal connection and an end of the other of said bars being pivotally mounted on the slat at a point spaced from said first mentioned pivotal connection, a lug extending from one of the bars, a stop means on one of said bars, a coil spring secured at its ends to the lug and the other bar respectively whereby when the bars are extending colinearly said coil spring is in tilted relation with said bars, said coil spring being adapted then to automatically shift said bars into intersecting relation past dead center until said stop means limits such shifting of the bars, and another coil spring secured at one of its ends to one of said bars and at the other of its ends to the second bar, adapted when the bed spring is in normal horizontal position, to urge the bars towards the aforesaid dead center position.

LOUIS HERZOG.
